Primary Examiner — Cynthia Ramirez*(74) Attorney, Agent, or Firm* — Knobbe, Martens, Olson & Bear, LLP(57) **CLAIM**

The ornamental design for a trash can trim component, as shown and described.

DESCRIPTION

FIG. 1 is a top, front, left-side perspective view of a trash can trim component of our design;

FIG. 2 is a top, rear, left-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof;

FIG. 8 is a bottom plan view thereof; and,

FIG. 9 is a partial cross-sectional view of a portion of a sidewall thereof, as designated in FIG. 7.

The broken lines shown in the figures are included for the purpose of illustrating environment and forms no part of the claimed design.
